ABSTRACT: An electric motor driven mutilated timing gear is manually set in either direction away from an "off" position. A signal device is held in "nonsignal" condition by a face of the gear. The gear is rotated towards the off position by a timing mechanism. When the gear reaches a signal position it releases the signal device and is decoupled from the timing mechanism.

MOTOR DRIVEN INTERVAL TIMING MECHANISM

CROSS-REFERENCES TO RELATED APPLICATIONS

Certain subject matter herein shown is disclosed and claimed in the copending patent application of myself and E. C. Knecht, Ser. No. 612,705, filed Jan. 30, 1967, now U.S. Pat. No. 3,440,370 and assigned to the same assignee.

BACKGROUND OF THE INVENTION

1. Field of the Invention

The invention relates to an interval timing mechanism and it has particular relation to an interval timing mechanism which may be manually set in either direction away from an off position.

2. Description of the Prior Art

In a conventional mechanism for measuring a selected time interval, a gear has an off position. The gear is manually moved away from the off position to an extent corresponding to the duration of the interval to be measured. Timing mechanism is coupled to the gear for the purpose of returning the gear towards the off position at a controlled rate. When the gear reaches a "signal" or "buzz" position, a signal is sounded to indicate the end of the interval. The gear then is manually returned to its off position.

One type of prior art mechanism permits movement of the gear in only one direction away from the off position. An example is shown in U.S. Pat No. 2,993,099 which issued July 18, 1961.

In another type of prior art mechanism the gear may be moved in either direction away from the off position. An example is found in U.S. Pat. No. 2,886,106 which issued May 12, 1959. As shown in FIG. 18 of this patent a pin 304 is received in a notch 313 in the off position.

SUMMARY OF THE INVENTION

In accordance with the invention an interval timing mechanism includes a mutilated gear which has an off position, a signal or buzz position and any one of a number of positions which may be manually selected to measure a desired interval. A signal device has a control member biased against one face of the gear to hold the signal device in nonsignaling condition. When the gear reaches its signal position a recess in the gear clears the control member to permit production of a signal. The gear is manually movable to an off position established by the configurations of the gear and control member, and may be manually moved from the off position in either direction.

It is therefore an object of the invention to provide an interval timing mechanism which has timing, signal and off positions determined by the relationship between a gear and a control member coacting with the gear.

It is another object of the invention to provide a mechanism as defined in the preceding paragraph wherein the gear has a cam surface and the control member constitutes a cam follower for the cam surface.

BRIEF DESCRIPTION OF THE DRAWING

Other objects of the invention will be apparent from the following description taken in conjunction with the accompanying drawing, in which:

FIG. 1 is a view in cross section with parts broken away of an interval timing mechanism embodying the invention;

FIG. 2 is a view in perspective with parts broken away of the mechanism of FIG. 1;

FIG. 3 is a view in front elevation of a mutilated gear, with a follower associated therewith;

FIG. 4 is a view taken on the line IV-IV of FIG. 3; and

FIGS. 5 and 6 are views similar to FIG. 4 but representing time displaced positions of the illustrated parts.

DESCRIPTION OF THE PREFERRED EMBODIMENTS

FIG. 1 illustrates a timing mechanism including an hour hand H and a minute hand M which are mounted for rotation about a common axis A and which are associated with a dial (not shown) in a conventional manner to indicate the time of the day. An interval pointer I is also mounted for rotation about the same axis for selecting an interval of time which is to be measured. The interval pointer may coact with a dial (not shown) which is calibrated to indicate the angular position of the pointer about its axis in terms of the time intervals represented by various pointer positions up to the maximum permitted by the drive. Although the drive may be arranged for different maximum intervals, a maximum interval of 60 minutes is frequently employed.

Spaced supporting plates 1 and 3 are provided for the mechanism associated with the hands H and M and the pointer I. The hand H has a hub which is a press fit on a tubular sleeve H1. The sleeve H1 is mounted for rotation about the axis A in a bushing B which is secured to the plate 1.

The minute hand M has a hub which is a press fit on a sleeve M1 which is mounted within the sleeve H1 for rotation about the axis A relative to the sleeve H1. The sleeve M1 carries a pinion M2 which is coupled through gearing G to a gear H2 secured to the sleeve H1 for the purpose of revolving the hour hand H once for each 12 revolutions of the minute hand M.

The pinion M2 has mounted thereon for independent rotation about the same axis a gear 5 which is biased against the pinion by a spring S to form a slip clutch which transmits sufficient torque to permit operation of the hands H and M by the motor 7. However, when the hands are to be manually set to a different time indication, the slip clutch slips to permit such setting.

The gear 5 is driven by a pinion 11 which is rotated from the synchronous motor 7 through a gear 13 and other gearing (not shown).

As shown in FIG. 1, a mutilated gear 9 and its hub 9A are die cast as an integral structure which is slidably splined to a shaft 15 for rotation with the interval pointer I. The shaft 15 extends through the sleeve M1 and has a square section 15A which is slidably received in a square opening in the hub 9A. A clapper 17 of soft-magnetic resilient sheet material has one end secured to the plate 3 by means of a rivet 19 and has a second end shaped as a finger 17A riding on the upper face of the gear 9 as viewed in FIG. 1. The resilience of the clapper material biases the finger 17A lightly against the face of the gear. The clapper also has a portion 17B extending adjacent but spaced from the core of a synchronous motor 7. Thus, if the clapper is free, it will vibrate under the influence of the alternating field developed by the motor 7 to produce a buzzing sound. However, when the finger 17A is in engagement with the face of the gear 9 as shown in FIG. 4, the clapper is prevented from vibrating. FIG. 4 is assumed to show the parts in the positions they occupy one-half minute before a buzz position.

In order to release the clapper at the proper time, the gear 9 is provided with an aperture or recess 21 which is so located that at the end of the interval being measured by the rotation of the gear 9 in the direction of the arrow 23 the recess 21 moves beneath the finger 17A to a buzz position shown in FIG. 5 and clears the finger for the purpose of releasing the clapper 17. In this position the mutilated gear is decoupled from its driving source represented by a pinion 25. The resulting buzzing sound produced by the clapper signifies the end of the interval being measured.

The pinion 25 is mounted for independent rotation on the same shaft as the gear 13 and has a slip coupling to the gear through a spring S1. The slip coupling transmits sufficient torque to assure timed rotation of the gear 9 by the synchronous motor 7. However, when the knob K is operated to set the interval pointer I, the slip coupling slips to permit such setting.

As shown in FIG. 4 a number of teeth are omitted from the mutilated gear 9. In the buzz position the pinion 25 is adjacent to the area of the gear 9 from which the teeth are omitted and consequently is decoupled.

When the buzzer is to be turned off the shaft 15 is rotated manually by the knob K to move the gear 9 to an off position. During such movement the finger 17A rides over a rib 21A formed on the gear 9 to the off position shown in FIG. 6. In this position the gear prevents vibration of the finger and is still decoupled from its driving source. When a new interval is to be measured the knob K is rotated manually in either direction to move the gear to the desired time position. The mutilated gear now is coupled to its driving source for timed movement by the motor 7 in the direction of the arrow 23.

When the knob K is pressed downwardly as viewed in FIG. 1 for the purpose of setting the associated clock, the square section 15A slides downwardly in the hub 9A but the coupling is such that the shaft and the gear 9 continue to rotate as a unit. The downward movement couples the components 29 and 31 of a jaw clutch which are biased by a spring S2 towards decoupled positions. When the clutch is in coupled condition rotation of the knob K rotates the sleeve M1 and sets the clock in a manner understood in the art. The construction materially simplifies the association of the gear 9 with the remainder of the assembly and the structure required to control the clapper 17.

Preferably the gear 9 is die-cast from a suitable diecasting alloy, such as an aluminum base diecasting alloy. The diecasting operation simultaneously forms the hub 9A, the teeth, the recess 21, and the rib 21A. In addition a shoulder 21C is formed for the purpose of retaining the finger 17A in the off position. However the shoulder 21C and the rib 21A have slopes selected to permit manual movement of the gear away from or to the off position in either direction by application of a reasonable torque to the knob K such as 9 to 16 inch-ounces. For example the edge 21D of the shoulder which is adjacent to the finger 17A in the off position may be inclined 17° or 18° away from the vertical as shown in FIG. 6.

In effect the finger 17A acts as a cam follower for a cam formed by the face of the gear 9. When the interval timing mechanism is not in use, the finger 17A occupies the off position shown in FIG. 6. In this position the finger is held displaced against its bias to an extent such that it and the clapper 17 cannot vibrate.

The off position of FIG. 6 locates the finger 17A in a trough bordered by the rib 21A and the shoulder 21C. When a time interval is to be measured, the gear 9 is rotated manually to an angular position corresponding to the interval to be measured. This movement may be either clockwise or counterclockwise. The configuration of the finger 17A and the trough are such that a noticeable torque such as 9 to 16 inch-ounces must be applied to move the shoulder 21C to the left as viewed in FIG. 6. This provides a noticeable stop or dwell "feel" which informs the operator that he has reached the off position, but permits the operator to move the gear 9 in either direction from the off position without requiring a burdensome physical effort by the operator.

Preferably the parameters are such that the effort required to move the gear 9 clockwise from the off position is slightly larger than that required to move the gear counterclockwise from the off position. This is illustrated in FIG. 6 by the height of the shoulder 21C which is higher than the rib 21A. Moreover the rounded cross section of the rib 21A and the bevel of the finger 17A make it noticeably easier to move rib past the finger 17A than to move the shoulder 21C past the finger. Such construction further assists the operator in sensing the arrival of the gear 9 at the off position.

Assuming that the gear 9 has been moved to the position corresponding to the desired interval, the motor 7 now moves

the gear 9 at a uniform rate in the direction of the arrow 23 in FIGS. 3 and 4 until the gear reaches the position represented in FIG. 4 which corresponds to say one-half minute before the expiration of the desired interval. The torque applied by the motor to the gear 9 to produce the timing movement of the gear preferably should be relatively small, and preferably should be appreciably less than the torque required to move the gear away from the off position. During this movement the face of the gear maintains the finger 17A elevated against its bias sufficiently to prevent vibration of the clapper 17.

Continued motion of the gear 9 finally moves the recess 21 below the finger, and the clapper is now free to buzz, signaling the end of the interval. Also the mutilated gear 9 now presents its tooth-free peripheral portion to its driving gear, and the resultant decoupling assures continuance of the buzz or signal until the gear 9 is reset manually.

It should be noted that the invention minimizes the number of parts utilized for providing the desired operation. The gear 9 is required for timing purposes. The clapper 17 is required as a source of sound. No other individual part is required. The finger 17A is formed as an extension of the clapper. The cam surface for the finger 17A to follow is formed on the gear 9.

I claim:

1. An interval timing mechanism comprising a stator structure, a rotor disc mounted for rotation about an axis relative to the structure, motive means including an electric motor for rotating said disc, said motor when energized producing an alternating magnetic field, a clapper unit resiliently mounted on said stator structure and having a portion disposed in the magnetic field for application of a magnetic force by said field to produce sound, said clapper unit having a finger bearing against one surface of said disc to prevent vibration of the clapper unit over a substantial range of rotation of said disc, said disc surface having a recess for receiving the finger in a first angular position of said disc to free the clapper unit for vibration by said field to produce sound, said disc surface having a configuration at a second angular position of said disc within said range coaxing with said finger for inhibiting movement of the disc away from said second angular position, said configuration permitting movement of the disc away from the second angular position in each direction in response to an application of torque thereto only if such torque is larger than the torque required to rotate the disc over a substantial part of said range.
2. Mechanism as claimed in claim 1 wherein said rotor disc comprises a mutilated gear, said motive means comprising gearing coupling the mutilated gear to the motor, said mutilated gear having no teeth engaging said gearing when the disc occupies said first and second angular positions, said mutilated gear including said disc surface being constructed integrally of homogeneous material.
3. Mechanism as claimed in claim 2 wherein said mutilated gear including said disc surface and said recess is molded from a molding material.
4. Mechanism as claimed in claim 2 wherein said disc surface comprises one face of said mutilated gear, said recess extending axially from said one face, said configuration comprising a trough in said one face for receiving said finger, the walls of said trough permitting rotation of said disc in each direction to force the finger out of the trough.
5. Mechanism as claimed in claim 4 wherein said trough and finger are configured to require a larger torque to produce rotation of the rotor disc in one direction than the torque required to produce rotation of the rotor disc in the other direction away from the second angular position.
6. Mechanism as claimed in claim 5 wherein said mutilated gear including the disc surface are molded from a diecasting metal alloy.
